UNITED STATES PATENT OFFICE

2,212,285

TEMPERATURE CONTROLLED HEATING
APPARATUS

William Ayers, Evanston, Ill.

Application January 24, 1938, Serial No. 186,701

2 Claims. (Cl. 236—92)

My main object is to provide improvements in heating apparatuses to the end of more satisfactorily controlling the operation of the apparatus and produce more uniform heating of the space to be heated.

Another object is to provide for the nearest approach possible to such regulation of the heater as to compensate at all times for the leakage of the heat units from the space to be heated, regardless of the outdoor temperature.

Another object is to provide improvements in heaters in which a heating medium is generated, by any suitable means, as for example gas or oil, or electricity, all of which, for the purpose 15 of this application will be treated as "fuel" heaters, to the end of rendering the supply of fuel to the heater controllable automatically from temperature conditions, to increase the flow of fuel to the heater as the temperature lowers and 20 decrease the flow of the fuel to the heater as the temperature rises; the fuel flow changing responsive to each change in temperature conditions, as distinguished from a condition in which the fuel supply to the heater is either fully open, or 25 fully closed, or in addition at a few selected temperatures, a retarded flow of fuel to the heater is provided for; and other objects as will be manifest from the following description.

Referring to the accompanying drawing: 30 Figure 1 is a view in elevation, partly diagrammatic, of apparatus embodying my invention; and

Figure 2, an enlarged sectional view of the heater element of the installation.

I have chosen to illustrate my invention as applied to a gas heater the operation of which is controlled responsive to changes in the outdoor temperature. The gas heater shown at 3 may be utilized to heat the room or rooms to be heated, in any desirable way and by any desirable medium. The gas heater, by way of example, may form a part of a hot water boiler in a hot water heating system.

The burner of the heater is represented at 45 and is shown as located in a fire box 5 the inlet end 6 of the burner, as is customary, flaring outwardly. A pipe 7 for supplying gas to the burner extends through the front wall 8 of the fire box and into the inlet 6 of the burner and in spaced 50 relation thereto.

The front wall 8 of the fire box contains a circular series of openings 9 surrounding the pipe 7 and communicating with the burner inlet 6 to supply thereto primary combustion supporting air, and a second circular series of openings

10 for supplying secondary combustion supporting air to the discharge from the burner 4. A circular shutter 11 is rotatably mounted on the front wall 8 of the fire box concentric with the series of openings 9 and 10 and contains segmental slots 12 spanning the openings 9 and 10, whereby upon rotating the shutter the effective sizes of the openings 9 and 10 may be varied from substantially zero to a maximum, to thereby provide for the supplying to the heater of the proper amount of primary and secondary air to be supplied to the gas flowing into the burner as hereinafter described.

It is the more usual practice in service gas installations to provide each building to be supplied with gas, with a gas pressure regulator located within the building and serving to insure the delivery of the gas to its point of use at a pressure not exceeding a predetermined pressure regardless of the pressure in the mains. Such a regulator, modified, however, as hereinafter explained, is shown at 13. It comprises a casing 14 having a partition 15 and a movable diaphragm 16 dividing it into a high pressure chamber 17, an intermediate low pressure chamber 18 and 20 an upper chamber 19 the partition 15 having an opening 20 providing a valve seat 21 for a valve 22 connected with the diaphragm 16. The regulator 13 is interposed in the service line 7 ahead of the burner 4 whereby the burner receives its gas supply from the low pressure chamber 18.

The diaphragm 16, and therefore the valve 22, are spring loaded as by the compression spring shown at 23 as customarily provided, whereby it is necessary that a certain pressure of gas build up in chamber 18, depending upon the resistance of the spring 23, before the valve 22 will close, the greater the pressure permitted to build up in chamber 18 the greater the flow of gas to the burner.

In accordance with my invention, considering this particular embodiment thereof, I automatically regulate the amount of pressure which may be built up in chamber 18 and thus the rate of flow of gas to the burner, responsive to changes in the outdoor temperature. As the outdoor temperature lowers the resistance of spring 23 is caused to be increased requiring the attainment of a higher pressure of gas in the chamber 18 before the valve 22 will close; and as the outdoor temperature rises, the resistance of the spring 23 is caused to be decreased requiring the attainment of a lower pressure of gas in the chamber 18 before the valve 22 will close.

In the arrangement shown I provide a spring tensioning member 24 comprising a rod 25 slideable in the casing 14 and having a head 26 which bears against the upper end of the spring 23.

- 5 The rod 25 presses against the underside of a lever 27 hinged at 28 to an upright 29 on a bracket 30 secured to the casing 14. A tension spring 31 connected with the bracket 30 and adjustably with the lever 27 and of greater strength than 10 the spring 23, forces the lever 27 against the rod 25 and thus compresses the spring 23, except as restrained by the controlling mechanism now to be described.

Interposed between the bracket 30 and the 15 lever 27 is a bellows-like expandable and contractible member 32 closed except for connection with a tube 33 which leads to a point outside of the building in which the heater is located and is there provided with a bulb 34 exposed to the outdoor 20 temperature.

The bulb 34, tube 33, and member 32, constituting a thermostat device, are closed to the atmosphere and contain any suitable fluid which, in contracting and expanding under variations in 25 the outdoor temperature, controls, through the member 32, the position of the lever 27 and consequently the degree to which the diaphragm 16 is spring loaded.

In practice it will be found desirable to so condition 30 the mechanisms described that at say 72° F. outdoor temperature, the member 32 will be expanded by the actuating fluid to such an extent that the loading of the spring 23 is negligible and thus no, or practically no, gas is supplied to 35 the burner; but as the outdoor temperature decreases the fluid in the thermostat device contracts permitting the spring 31 to lower the lever and increase the spring load on the diaphragm 16 and the valve 22, thus opening the latter and setting 40 the regulator for the maintaining at this temperature of a high degree of gas pressure; and as the outdoor temperature rises the fluid expands, thus lifting the lever 27 and reducing the spring load on the valve 22.

45 The pressure of the gas flowing to the burner 4 will be varied whenever a temperature change in the outdoor atmosphere occurs, the parts of the apparatus being so proportioned and arranged that there will be supplied to the burner 50 automatically approximately that amount of gas necessary to maintain a predetermined temperature, say 72° F. in the building to be heated regardless of the outdoor temperature, the varying of the pressure of gas being directly responsive to each atmospheric change, approximately 55 uniformity of heating is effected.

As the air supplied to the heater for primary and secondary combustion should vary with the pressure of the gas, less air being supplied to the 60 burner as the gas pressure to the burner decreases, and vice versa, provision is made for automatically accomplishing such control of the air. This is effected by connecting an arm 35 on the shutter 11 with the lever 27, as by means of 65 the adjustable link connection 36, the shutter 11 rotating in a direction to afford increased air entry to the heater as the lever 27 swings downward responsive to a drop in the outdoor tem-

perature, and rotating in a reverse direction to reduce air entry to the heater as the outdoor temperature rises.

Sometimes a plurality of heaters, in practice, are connected with a single gas pressure regulator 5 so located as to be subject to the temperature of the outdoor atmosphere. My invention may also be applied to such installations, in which case the outlet 7 of the described structure would be branched to lead the gas to the plurality of heaters. 10

While I have illustrated and described a particular embodiment of my invention and have also described a modification thereof, I do not wish to be understood as intending to limit it 15 thereto, as the same may be variously modified and altered and the invention embodied in other forms of structure without departing from the spirit thereof. Thus by way of example, any other suitable form of temperature controlled 20 means may be used if desired to regulate the fuel-flow controller.

What I claim as new and desire to secure by Letters Patent, is:

1. In combination with a gas-fired heater in an 25 enclosure, a conduit for conducting gas to the heater, a gas-pressure regulator for controlling the gas pressure in said conduit having a spring-loaded valve-operating diaphragm and temperature-controlled means for controlling the loading 30 of said diaphragm operative, upon each temperature decrease exterior to said housing to increase the load on said diaphragm to increase the pressure of gas in the conduit and upon each temperature rise to decrease the load on the diaphragm to decrease the pressure of gas in said 35 conduit, said means comprising a movable member for controlling the loading of the diaphragm, a spring urging said member in a direction to increase the load on the diaphragm, and a movable 40 element controlled by the temperature exterior of said enclosure acting on said member in opposition to said last-referred-to spring.

2. In combination with a gas-fired heater in an 45 enclosure, a conduit for conducting gas to the heater, a gas-pressure regulator for controlling the gas pressure in said conduit having a spring-loaded valve-operating diaphragm and temperature-controlled means for controlling the loading 50 of said diaphragm operative, upon each temperature decrease exterior of said enclosure to increase the load on said diaphragm to increase the pressure of gas in the conduit and upon each temperature rise to decrease the load on the diaphragm to decrease the pressure of gas in said 55 conduit, said means comprising a movable member for controlling the loading of the diaphragm, a spring urging said member in a direction to increase the load on the diaphragm, a closed course containing an expandable and contractible 60 fluid, said course including a portion exposed to the temperature exterior of said enclosure, and an element movable responsive to the contracting and expanding of said fluid and operating upon the expansion of said fluid to move said movable member in opposition to said last-referred-to 65 spring.

WILLIAM AYERS.
